UNITED STATES PATENT OFFICE

144,331

DESIGN FOR A COUNTER RACK FOR PACKAGED COMMODITIES

Robert B. Wemyss, Louisville, Ky.

Application October 27, 1944, Serial No. 116,006

Term of patent 7 years

(Cl. D80—9)

To all whom it may concern:

Be it known that Robert B. Wemyss, a citizen of the United States, residing in Louisville, county of Jefferson, State of Kentucky, has invented a new, original, and ornamental Design for a Counter Rack for Packaged Commodities, of which the following is a specification, reference being had to the accompanying drawing, forming part thereof, wherein

Fig. 1 is a front perspective view of a counter rack showing my new design.

Fig. 2 is a rear perspective view of the rack.

I claim:

The ornamental design for a counter rack for packaged commodities, substantially as shown.

ROBERT B. WEMYSS.
